United States Patent Office.

MICAJAH C. BURLEIGH, OF SOMERSWORTH, NEW HAMPSHIRE.

Letters Patent No. 106,116, dated August 9, 1870.

IMPROVEMENT IN MECHANISM FOR ACTUATING THE PICKER-STAFF IN LOOMS.

The Schedule referred to in these Letters Patent and making part of the same.

To all persons to whom these presents may come:

Be it known that I, MICAJAH C. BURLEIGH, of Somersworth, in the county of Strafford and State of New Hampshire, have made a new and useful invention having reference to Mechanism for Actuating the Picker-Staff of a Loom; and do hereby declare the same to be fully described in the following specification and represented in the accompanying drawing, of which—

Figure 1 denotes a top view;

Figure 2, a side elevation; and

Figure 3, a longitudinal section of such mechanism with my improvement.

Figure 4 is a top view of the supporting-arm to be hereinafter described.

Figure 5 is an under-side view of picker-staff rocker-foot.

My improvement or invention consists in a peculiar arrangement of the operative spring and its pin of the picker-staff rocker-foot with the supporting-arm of the said foot, and with a yoke extended down from the foot, as hereinafter explained.

In such drawing—

A denotes the supporting-arm, as usually fixed to the lay of a loom, its upper surface, or that in which the rocker-foot B rests, being a plain surface.

Two teeth or projections, a a, extend up from opposite sides of the said surface, and with an interval or space, b, between them, they being arranged near the middle of the arm.

These teeth also project beyond the opposite sides of the arm, so as to constitute abutments or shoulders for a yoke, C, to rest against.

The said yoke projects downward from the rocker-foot B, and embraces the arm A on its opposite edges, and has a hole, c, made through its transverse connection r, to receive a pin, D, which extends through it in manner as represented, and is encompassed by a helical spring, E.

The pin and spring stand obliquely to the arm A, the pin at its upper end being pivoted to the arm, and

there being provided with a head or shoulder, e, for one end of the spring to rest against.

The rocker-foot B is formed with two niches or recesses, f f, to receive the teeth a a in manner as represented, the tread or bearing-surface of the foot being extended between such niches f f in manner as represented.

From the above it will be seen that there is not one tooth or projection carried entirely across the supporting-arm, and, to operate with a niched recess, carried entirely across the rocker-foot, for when such is the case, there is not a continuous bearing of the rocker-foot, such as there is when the two projections and niches are employed, and arranged with the rocker-foot and arm as hereinbefore explained.

Without the continuous bearing the operative parts are not so well supported, and are more liable to be noisy when in use.

The picker-staff, by means of a clamp, is to be fixed to a socketed projection, h, raised on the rocker-foot, or making part thereof.

With my arrangement of the several parts, the spring is so disposed as to operate to excellent advantage, and is not liable to easily become broken under the sudden action of the picker-staff.

I would observe that I make no claim to a rocker-foot and a supporting-arm combined with a picker-staff and the lay of a loom, and having a spring for retracting the foot after each throw of the picker-staff, the object of the rocker-arm being to cause the shuttle-nose bearing part of the arm, or the picker thereof, to travel in a horizontal line.

I claim—

The spring E, its support-pin D, the yoke C, the arm A, and the rocker-foot B, the whole constructed, combined, and arranged substantially as described.

MICAJAH C. BURLEIGH.
